THYRATRON CATHODE DESIGN TO PRE-
VENT CLEANUP OF HYDROGEN

Jerome Rothstein, Belmar, N. J.

Application April 22, 1946, Serial No. 663,856

8 Claims. (Cl. 313—180)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a thyatron cathode arrangement which prevents clean up of hydrogen or other gas employed.

One object of this invention is to provide a cathode whose geometry is such that a reservoir of a hydride, or other suitable compound of the gas employed, is formed automatically during the processing of the tube, or which compound is provided beforehand and which supplies hydrogen or other gas as the gas in the tube cleans up.

Another object is to provide such a thyatron cathode in which no special capsules or heater circuit arrangements are necessary.

Still another object is to provide such a thyatron cathode in which all ratings and characteristics are the same as the prototype tube.

These and other objects will become apparent in the specification and in the appended drawing in which:

Figure 1 is a vertical, cross-sectional view of the electrodes of the tube, and

Figure 2 is a vertical, cross-sectional view of the cathode and hydrogen reservoir within the cathode.

Referring to Fig. 1 which illustrates the assembled thyatron elements in perspective cross section showing a well known arrangement in which a radiation shield 10 covers the major portion of the cathode assembly. The cathode is heated in the usual fashion by means of a heater wire 11 wound spirally about the cathode body 12. The heater wire, which is preferably covered with a layer of insulating material such as aluminum oxide, is held against the cathode body by means of corrugated strips 13. The top of the cathode is preferably partially closed by inwardly extending annular disc member 14. The cathode is provided at its inner surface with a plurality of radial vanes 15 extending approximately half way to the center of the cathode body. Spaced from the inner ends of the vanes is a baffle extension 16 which is attached to and depends from a baffle 17 supported on legs 18 abutting and attached to member 14. This baffle extension is cylindrical in shape and is made preferably of nickel.

The entire cathode assembly is housed within, but insulated from, a cylindrical member 19 which carries screen 20. Welded, or otherwise suitably attached, to the screen are grid 21 and

2

cover member 24. Plate 22 is connected to lead 23 which together with the remainder of the structure shown is intended to be sealed in the usual glass envelope 26 to constitute a thermionic tube.

Extension 16, upon the characteristics of which depend the functioning of this cathode to prevent clean up of hydrogen or other gas, is placed into the cathode and into the tube in a perfectly clean condition. As is well known, in the vast majority of commercial tubes the material effective in providing the cathode with its electron emissive properties is a mixture of oxides of the alkaline earth metals containing excess barium. Alkaline earth carbonates are originally deposited on the cathode base metal. Heating in vacuo converts the carbonates to oxide and allows reducing agents in the base metal to react with the oxides and free some barium, one of the alkaline earth metals. Conversion to oxide and activation of the cathode to produce free barium together constitute processing of the cathode according to conventional uses. Accordingly, in one embodiment using hydrogen, during the processing of the tube the cathode is run overheated so that the barium is freed in the usual fashion from the conventional alkaline earth coating constituting the emitting surface of the cathode body 12 and vanes 15, the free barium being deposited onto the baffle extension 16. The physical location of the baffle is such that its upper end is maintained cool due to conduction and radiation from the baffle and the feet, while the inner end is maintained quite hot due to the heating action of the cathode wires. Points intermediate the ends of the baffle extension are at temperatures intermediate the temperatures found at the respective ends.

At some zone along this extension, as at 25, the temperature will correspond to that of the correct hydrogen pressure from the dissociation of barium hydride formed in the tube when hydrogen is admitted. At points below 25 the available barium remains as barium while above point 25 the barium is found in combination as barium hydride. The tube is, of course, initially filled with hydrogen at the desired pressure. Thus, the barium below point 25 would be free to migrate to point 25 or above and there form barium hydride. This baffle extension therefore, acts as a hydride capsule and has the advantages of an extremely simple construction which is adaptable to any cathode geometry. Furthermore, it is obvious that no separate heater for

the capsule is required as in the conventional barium hydride capsule. In addition, it is apparent, in this embodiment, that no barium hydride need be previously prepared, the formation of the hydride occurring in the tube from the hydrogen and the barium already present. Another advantage lies in the fact that the barium hydride formed on the extension is as reproducible as the cathode from which it is made. The reservoir zone, which corresponds to the outer surface of cylinder 16 in Fig. 1, is thus automatically maintained at the correct temperature for the desired pressure, and even if the tube is run at higher power with the cathode reaching higher than normal temperatures, the reservoir zone will automatically be driven to the region of desired temperature because of dissociation of the barium hydride and migration of the barium to a new region higher up than region 25 with recombination of the barium to form barium hydride.

Thus, there is provided a simple, economical and an efficient cathode geometry so modified that barium hydride is formed automatically during the processing of the tube and which supplies hydrogen at practically the same rate as that at which the hydrogen in the tube cleans up.

In another embodiment which is illustrated in Fig. 2 member 16 is filled beforehand with a suitable hydride 200 such as titanium or zirconium hydride. The temperature distribution is substantially as described above and the mode of operation is the same, hydrogen now being replenished by dissociation of the hydride employed. For extremely high power applications this embodiment is preferable to the former because the high rate of hydrogen clean up may exceed the capabilities of the small reservoir described previously.

It is obvious that if a gas other than hydrogen is employed a suitable compound of that gas or material which absorbs that gas and is previously saturated therewith may be used in member 16 to provide by its dissociation or desorption respectively, gas to replenish that cleaned up during operation.

While I have shown a single embodiment of the invention it is obvious that other shapes, arrangements and geometries are possible and will readily occur to those skilled in the art, and I therefore do not intend to limit my invention except within the scope and extent of the appended claims.

I claim:

1. A hydrogen filled thermionic tube, including a metallic member supporting a hydride capable of releasing hydrogen upon being heated, a cathode spaced from said member and capable of heating a portion of said member, and a cooling baffle connected to another portion of said member to establish a thermal gradient along said metallic member.

2. A hydrogen filled thermionic tube including a thermionic cathode, a metallic member, one portion of which is positioned in heat radiation intercepting relationship with respect to said cathode, said member extending away from said cathode whereby another portion of said mem-

ber is beyond direct interception of said radiation, and a metallic hydride supported by said member.

3. A hydrogen-filled thermionic tube as defined in claim 2 wherein said hydride is barium hydride.

4. A hydrogen-filled thermionic tube as defined in claim 2 in which said metallic member is a hollow, partially closed cylinder, and said metallic hydride is within said cylinder.

5. A hydrogen-filled thermionic tube including a metallic member mounted coaxially with the longitudinal axis of said tube, a hollow cathode surrounding said member, and a layer of barium hydride on the outer surface of said member for maintaining the operating hydrogen pressure in said tube.

6. A hydrogen-filled thermionic tube including a centrally-positioned metallic member, a hollow cathode surrounding said member but in spaced relationship from said member, whereby said member is heated by radiation intercepted from said cathode, and a metallic hydride deposited on the outer surface of said metallic member.

7. A hydrogen-filled thermionic tube including a cathode, a metallic member, one portion of which is positioned near the electron emitting surface of said cathode, another portion extending beyond said cathode, a hydride of an alkaline earth metal supported by said member, one portion of said member being in heat-radiation-intercepting relationship with respect to said cathode, a baffle within said tube, joined to said metallic member to be beyond direct interception of said radiation, whereby a temperature gradient exists along said member, the range of said temperature gradient including the temperature for which the hydride is in equilibrium with the desired hydrogen pressure within said tube.

8. A method of preparing a hydride reservoir for a hydrogen-filled thermionic tube provided with a metallic surface in the vicinity of a cathode, which includes the steps of preparing an electron-emitting coating on said cathode by converting alkaline earth carbonates to oxides, activating of said oxides with the resulting evaporation of the alkaline earth metallic by-products, collecting and condensing a substantial portion of said by-products on said metallic surface and subsequently admitting hydrogen into said tube for combining said metallic by-products with said hydrogen, thereby forming a reservoir of metallic hydride on said metallic surface.
